UNITED STATES PATENT OFFICE.

JAMES W. THOMPSON, OF WHAM, LOUISIANA.

VEHICLE-WHEEL.

No. 926,783.

Specification of Letters Patent.

Patented July 6, 1909.

Application filed June 17, 1908. Serial No. 438,999.

To all whom it may concern:

Be it known that I, JAMES W. THOMPSON, citizen of the United States, residing at Wham, in the parish of Ouachita and State of Louisiana, have invented certain new and useful Improvements in Vehicle-Wheels, of which the following is a specification.

The present invention belongs to the type of wheels having the rim portion movable 10 with reference to the hub portion and having cushioning means between the two.

The invention provides novel locking means between the parts to insure rotation thereof without interfering in the least with 15 the free yielding movements of the rim portion and at the same time bracing the wheel laterally to sustain lateral stress, as when making a curve, dropping into a rut or passing over an obstruction.

For a full understanding of the invention and the merits thereof and also to acquire a knowledge of the details of construction and the means for effecting the result, reference is to be had to the following description 25 and accompanying drawings.

While the invention may be adapted to different forms and conditions by changes in the structure and minor details without departing from the spirit or essential 30 features thereof, still the preferred embodiment is shown in the accompanying drawings, in which:

Figure 1 is a side view of a vehicle wheel embodying the invention, a portion of the 35 rim being broken away. Fig. 2 is a vertical section on the line $x-x$ of Fig. 1. Fig. 3 is a side view of the center frame, the ring on the near side and the coöperating disk being removed. Fig. 4 is a detail view of a modification showing double springs interposed between the hub and coöperating member. Fig. 5 is a detail view of a further modification, showing a pneumatic device interposed 40 between the parts of the center frame. Fig. 45 6 is a detail view in perspective of the side ring having the projections. Fig. 7 is a detail perspective view of the disk or plate, having the recesses to receive the projections of the side ring.

Corresponding and like parts are referred to in the following description and indicated in all the views of the drawings by the same reference characters.

The wheel comprises a rim, a center frame 55 constituting the hub portion and cushioning

means between the elements of the center frame.

The rim 1 may be of any construction and is connected to the outer member of the center frame by means of spokes 2.

The center frame consists of a hub 3, outer ring 4 and side rings 5, the latter being secured in any manner to the outer ring 4 and spaced apart a distance to receive the cushioning means, which latter are interposed 65 between the hub 3 and the outer ring 4.

The cushioning means may consist of springs 6, or a pneumatic device 7, which may be a tube or other inflatable structure. The springs 6 may be single or double. In 70 the latter construction one spring is made smaller than the other and inserted therein. In the event of the cushioning means being a pneumatic device, the latter fills the space between the hub 3 and rings 4 and 5. When 75 the cushioning means consist of springs, the latter have a radial arrangement and their end portions are fitted to studs 8 extended from the hub 3 and ring 4. Clips 9 serve to secure the springs 6 to the hub and ring 4 80 and are bolted or otherwise secured to the respective parts, the end portions engaging with the terminal coils of the springs being of hook form to engage with the latter. The inner spring of the double springs has its end 85 portions engaged with the ends of the studs 8. The outer side of the hub 3 and the inner side of the ring 4 may be of any form and are preferably of polygonal outline to form a plurality of straight faces to receive the 90 abutting ends of the springs 6. When a pneumatic device is employed, the opposing sides of the hub 3 and ring 4 are circular, so as to provide a uniform bearing upon the inner and outer sides of the pneumatic device.

The openings of the side rings 5 are closed by means of disks or plates, the same fitting close against the side rings to prevent dust and foreign matter from entering the space 10 of the center frame receiving the cushioning means. The end portions of the hub 3 are reduced and pass through openings of the disks or plates, the latter being secured to the shoulders formed at the inner ends of the reduced portions of the hub. The disks or plates move with the hub and their outer portions overlapping the side rings 5 brace the wheel laterally and sustain the lateral strain incident to the rounding of a curve,

the passing over an obstruction or the dropping into a rut. One of the disks or plates 10 has its inner side flat so as to move upon the adjacent ring 5 in every direction.

5 Interlocking means are provided between the other disk 11 and the adjacent ring 5 to limit the relative turning thereof, thereby preventing overstraining of the cushioning means. The interlocking means between 10 the disk 11 and the adjacent ring 5 are of such construction as to admit of a limited movement of the disk 11 in every direction so as to obtain all the advantages of the cushioning means in absorbing shock and 15 vibration. Projections 12 are formed or provided upon the outer side of the ring 5 adjacent to the disk or plate 11 and are of wedge form. Recesses 13 are formed upon the inner side of the disk or plate 11 and 20 correspond in outline to the shape of the projections 12. The projections 12 and recesses 13 are of such relative dimensions as to admit of the rim and hub portions of the wheel having a like limited play in every 25 direction. When the hub and rim portions of the wheel are relatively turned, the shoulders of the parts 12 and 13 abut after said parts reach the limit of movement and cause both to turn together, thereby preventing 30 overstraining of the cushioning means and insuring positive rotation imparted to one part of the wheel being transmitted to the other, this being of the utmost importance when the wheel is used as a driver for an 35 automobile or other mechanically propelled machine. The edges or walls of the interlocking elements 12 and 13 are undercut, thereby preventing relative outer strain upon the parts 11 and 5 when motion is 40 transmitted from one to the other.

There may be as many interlocking parts 12 and 13 as may be found necessary, but in practice two such parts are sufficient, the same having a diametric arrangement.

A cap 14 may be secured to the center 45 frame so as to extend over the disk or plate and thereby prevent dust or other foreign matter from finding its way into the joint formed between the disk and the adjacent ring 5. This cap 14 may be secured to the 50 ring 4 by the same fastening means employed for holding the side rings 5 in place.

Having thus described the invention, what is claimed as new is:

1. In a wheel of the character described, 55 comprising a center frame embodying a hub portion, a ring portion and interposed cushioning means, plates secured to said hub portion and overlapping the sides of said ring portion and serving to brace the wheel 60 laterally and to close the space between the hub and ring portions, and interlocking projections and recesses formed between a plate and the ring portion, said parts being of wedge form and of such relative proportions 65 to admit of the rim and hub portions of the wheel having a limited play.

2. In a wheel of the character described, comprising a center frame embodying a hub portion, a ring portion and interposed cushioning means, plates secured to said hub portion and overlapping the sides of said ring portion and serving to brace the wheel 70 laterally and to close the space between the hub and ring portions, and coöoperating projections and recesses forming interlocking 75 means between a plate and the said ring portion, the meeting portions of said parts being undercut to form positive interlocking means to prevent lateral displacement of the 80 plate and ring.

In testimony whereof I affix my signature in presence of two witnesses.

JAMES W. THOMPSON. [L. s.]
